UNITED STATES PATENT OFFICE.

MARLO D. PIGMAN, OF MIDDLETOWN, OHIO.

SUCTION BOX.

Application filed June 14, 1924. Serial No. 720,050.

To all whom it may concern:

Be it known that I, MARLO D. PIGMAN, a citizen of the United States, residing at Middletown, in the county of Butler and State 5 of Ohio, have invented certain new and useful Improvements in Suction Boxes, of which the following is a specification.

The invention relates to paper making machinery, and has as an object the provision 10 of an improved suction box for use in many locations in such machinery.

An object of the invention is the provision 15 of a suction box which shall be efficient in use, simple to produce, and which shall reduce wear upon the felt upon which the pulp is carried.

Further objects of the invention will appear 20 from the following description when read in connection with the accompanying drawing, in which—

Fig. 1 is a perspective view;

Fig. 2 is a central vertical longitudinal section, broken away to reduce its length;

Fig. 3 is a detail section, similar to Fig. 2, 25 the roll being omitted;

Fig. 4 is an end view from the left of Fig. 2;

Figs. 5 and 6 are transverse sections on line 5, 5 and 6, 6 of Fig. 2;

Fig. 7 is an end view from the right in Fig. 2;

Fig. 8 is a perspective view of the bottom plate;

Fig. 9 is a perspective view of the filler 30 strips;

Fig. 10 is a perspective view of the inner casing; and

Fig. 11 is a detail diagrammatic view 40 showing an application of the suction box of the present invention to a portion of a paper machine.

As shown, the device comprises end castings 10 and 11, each having flanges 12 and 13 inset from the edge, and carried along the 45 upper and side edges for the reception of an outer casing 14, shown as rectangular in cross section, and comprising three sides of a rectangular cylinder. The shell 14 is shown as seating upon the flanges 12 and 13, 50 which are inset from the edges of the castings 10, 11, sufficiently to allow the outer surface of the shell to become flush with the said edges. The shell may be secured to the flanges as by means of rivets, screws or the 55 like.

A base for the device is shown in the form

of a board, preferably of wood, 15, shown in perspective in Fig. 8. Upon this board the castings 12, 13 may be secured, as by means of bolts 16 passing through the board and 60 through the extensions 17, 18 upon the castings 10, 11. The edge of the casing 14 is shown as seating upon the board 15, and is provided with inturned flanges 19, 20 occupying a portion of the fourth side of the rectangular cylinder comprised by the casing 14. 65

To form a suction chamber within the casing 14, there is shown an inner casing 21, shown in perspective view in Fig. 10, comprising a substantially semi-cylindrical body 70 provided with out-turned flanges 22 on its lower edge.

The out-turned flanges 22 are shown as seating upon the flanges 19, 20 and may be secured thereto, as by screws 23 passed through the two, and into the board 15. The ends of the casing 21 are shown as abutting against the end walls of the castings 10, 11. 75

To permit fluid to flow from the interior of the casing 21 to the space between the same and the casing 14, the flanges 22 are shown as cut away to provide slots 24 closely adjacent to the lower portion of the suction chamber between the two casings. 80

To provide for the attachment of a suction pipe, the casting 11 is shown as formed with a cylindrical extension 25 over which a suction pipe may be slipped and secured in any desired manner. The inner end of the chamber 26 formed by the extension of the casting 11, is formed by a wall 27 of an outline upon the arc of a circle adapted to register with the end of the inner casing 21 to close the space within the casing 21 at this point. 85

To apply suction to a pulp bearing belt, there is shown a roller 28 journaled in cavities 29, 30 formed internally of the castings 10 and 11. The roller 28 is shown as formed with end members 31, 32 in the form of disks 33 bearing cylindrical flanges 34 and hub members 35, the latter provided with stub shafts 36 extending into the journal bearings 29, 30. Preferably the ends of the journal cavities 29, 30 are provided with counterbores, as at 37, 38. The shaft 36 may be formed separate from the hubs 35 and inserted therein, the members 31 and 32 preferably being formed of cast material, such as brass. The material named is suitable 90 material for all the metallic parts of the device, since it is not subject to rust. 95

100

105

110

The roll 28 is completed by means of a cylinder 39 fitting over the flanges 34 of the hubs 31, 32, and shown as perforated or formed of reticulated material. To provide a close fit with the surface of the cylinder 39, there are shown filler strips 40, 41 fitting within the side bars 42, 43 of the bottom board 15. The inner surfaces, 44, 45 of the strips 40, 41 are shown formed upon arcs of 10 a circle of slightly greater radius than the cylinder 28. As shown in Fig. 6, the roll 28 is adapted to project slightly below the surface of the board 15 and the filler strips 40, 41, and it is only the openings which 15 are exposed to the external atmosphere through which suction applied through a pipe in connection with the extension 25 can act. Since the roll 28 projects slightly as shown, the web will bear on the roll to almost the entire exclusion of friction against 20 the immovable surface of the board 15, thereby greatly reducing the wear upon the web.

The action of the device will be obvious from the above description. The box will 25 be placed so that the traveling web bearing the pulp will be in contact with the surface of the roll 28 when the web being drawn therealong will cause revolution of the roll, and suction being applied through the pipe 30 25 will cause water to be extracted from the web and pulp, to be drawn to the interior of the roll through the perforations or reticulations, through the slots 24 to the interior of the outer chamber between the castings 35 13 and 21, and away through suction pipe. The application of the device to a machine is diagrammatically shown in Fig. 11, wherein the box is placed above the felt to the lower surface of which the paper material 40 is adhering and preferably closely adjacent a couch roll. Obviously, one of the devices may be placed adjacent each of the couch rolls of a machine.

Minor changes may be made in the physical embodiment of the invention without departing from its spirit and within the scope of the appended claims.

I claim:

1. A suction box comprising, in combination, inner and outer spaced casings providing a chamber therebetween, means to apply suction to said chamber, a foraminous roller housed within said inner casing, means for communication between the interior of said 55 inner casing and said chamber, said roller adapted to be operated in contact with the web of a paper making machine.

2. A suction box comprising, in combination, inner and outer casings spaced to provide a suction chamber therebetween, said casing seated upon a base board having a roller slot, a foraminous roller housed within 60 said inner casing projecting through said

slot, means to produce suction within said chamber, and means providing communication between said chamber and the interior of said inner casing whereby water may be drawn from a pulp-bearing web in contact with said foraminous roller. 65

3. A suction box comprising, in combination, inner and outer casings spaced to provide a suction chamber therebetween, said casing seated upon a base board having a roller slot, the edges of said slot formed to closely fit the surface of the roller, a foraminous roller housed within said inner casing projecting through said slot, means to produce suction within said chamber, and means providing communication between said chamber and the interior of said inner casing whereby water may be drawn from a pulp-bearing web in contact with said foraminous roller. 70 75 80

4. A suction box comprising, in combination, end members each having a shoulder adjacent its edge, an outer casing seated upon said shoulder, an inner casing spaced from said outer casing and abutting against the inner surface of said end members, said inner casing having passages placing its interior in communication with said chamber, means carried by one of said members for attachment of a suction pipe in communication with the chamber, a foraminous roller journaled in said members and housed within 90 said inner casing, a base board having a longitudinal slot through which said roller protrudes, the edges of said slot closely fitting the surface of said roller whereby moisture may be drawn from a pulp-bearing web 95 100 in contact with a protruding portion of the surface of said roller.

5. A suction box comprising, in combination, end members, an outer casing joined to said end members having an open side with edge flanges extending into said opening, an inner casing having outwardly turned flanges seating upon said inturned flanges, the ends of said inner casing abutting the inner surface of said members whereby a 110 chamber is provided between said casings, a foraminous roller journaled in said members and housed within said inner casing, a base board upon which said members and outer casing seat and provided with a slot through 115 which said roller protrudes, the edges of said slot formed to closely fit the surface of said roller, means carried by the exterior of the device for attachment of a suction pipe to exert suction within said chamber, said 120 inner casing having passages to place its interior in communication with said chamber, whereby moisture may be drawn from a pulp bearing web in contact with a protruding portion of the surface of said roller.

MARLO D. PIGMAN.
